DESIGN FOR A CORNER PLATE FOR CASKETS

John E. Burkard, Detroit, Mich., assignor to
Victor Casket Hardware Co., Galesburg, Ill., a
corporation of Illinois

Application May 16, 1934, Serial No. 51,806

Term of patent 7 years

To all whom it may concern:

Be it known that I, JOHN E. BURKARD, a citizen of the United States, and a resident of the city of Detroit, county of Wayne, and State of Michigan, have invented a new, original, and ornamental Design for a Corner Plate for Caskets, of which the following is the specification, and reference being had to the accompanying drawing, forming a part thereof.

Figure 1 is an elevational view of one side of a

corner plate for caskets, showing my new design; and

Figure 2 is a top plan view thereof.

The other side of this corner plate bears the same surface ornamentation as is disclosed in Figure 1.

I claim:

The ornamental design for a corner plate for caskets as shown and described.

JOHN E. BURKARD.
